US00D346696S

United States Patent [19]

Simone et al.

[11] Patent Number: Des. 346,696

[45] Date of Patent: ** May 10, 1994

[54] TOOTHBRUSH HANDLE

[75] Inventors: **John A. Simone**, Bayonne, N.J.;
Adam Sherman, Brooklyn, N.Y.;
James C. McKinney, Cranbury;
Thomas E. Mintel, Rahway, both of
 N.J.

[73] Assignee: **Colgate-Palmolive Company**, New
 York, N.Y.

[**] Term: **14 Years**

[21] Appl. No.: **603,639**

[22] Filed: **Oct. 25, 1990**

[52] U.S. Cl. **D4/104**

[58] Field of Search **D4/104-114,**
D4/134, 136, 138; 15/143.1, 159.1, 160,
167.1-167.3

[57] CLAIM

The ornamental design for a toothbrush handle, as shown and described.

DESCRIPTION

FIG. 1 is a side elevational view of a toothbrush handle showing our new design;

FIG. 2 is a top plan view thereof;

FIG. 3 is a bottom plan view thereof;

FIG. 4 is an elevational view of the other side thereof; and,

FIG. 5 is a perspective view thereof.

The broken line showing of bristles is for illustrative purposes only and forms no part of the claimed invention.
